USPC **D24/189**

CLAIM

(58) **Field of Classification Search**

The ornamental design for a part of a positioning marker of hemostatic device, as shown and described.

USPC D24/127, 130, 133, 146, 147, 189, 190,
D24/191, 192

DESCRIPTION

CPC A61F 13/00; A61F 13/023; A61F 15/008;
A61F 15/004; A61F 13/024; A61F
13/0246; A61F 2013/00412; A61M
2025/0246; A61M 25/02; A61M 25/024;
A61M 25/0266; A61M 25/0253

FIG. 1 is a perspective view of a part of a positioning marker of hemostatic device, showing our new design;
FIG. 2 is a front view thereof, the rear view being a mirror image thereof;

See application file for complete search history.

FIG. 3 is a right side view thereof;

(56) **References Cited**

FIG. 4 is a left side view thereof;

FIG. 5 is a top view thereof;

FIG. 6 is a bottom view thereof; and,

FIG. 7 is an enlarged end elevational view taken along line 7-7 between line 7-7 in FIG. 5.

The broken lines illustrate portions of the part of a positioning marker of hemostatic device that form no part of the claimed design.

1 Claim, 7 Drawing Sheets
